Primary Examiner — Jae Liang*Assistant Examiner* — Christopher Torma(74) *Attorney, Agent, or Firm* — Jiwen Chen; Joywin IP Law PLLC(57) **CLAIM**

The ornamental design for a desk leg as shown and described.

DESCRIPTION

FIG. 1 is a first perspective view of a desk leg showing the design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of a portion of FIG. 1.

The small evenly spaced dash lines in the drawings depict portions of the desk and form no part of the claimed design. The dot-dash broken lines encircling portions of the desk leg in FIG. 1 and illustrated in enlarged views in FIG. 9 form no part of the claimed design.

1 Claim, 7 Drawing Sheets(56)
